(57) **CLAIM**

The ornamental design for a bottle, as shown and described.

DESCRIPTION

FIG. 1 illustrates a front perspective view of a bottle showing our new design;

FIG. 2 illustrates a front elevation view thereof, wherein the rear elevation view is an identical image of this view;

FIG. 3 illustrates a right side elevation view thereof;

FIG. 4 illustrates a left side elevation view thereof;

FIG. 5 illustrates a top view thereof; and,

FIG. 6 illustrates a bottom view thereof.

The evenly dashed broken lines in the drawings illustrate the portions of the design that form no part of the claim. The dot-dot-dash broken line in the FIG. 6 bottom plan view defines the bounds of the claim and forms no part thereof.
